UNITED STATES PATENT OFFICE.

RUFUS N. BOREN, OF MARIETTA, MISSISSIPPI.

IMPROVEMENT IN STRAW-CUTTERS.

Specification forming part of Letters Patent No. **178,102**, dated May 30, 1876; application filed March 11, 1876.

To all whom it may concern:

Be it known that I, RUFUS N. BOREN, of Marietta, in the county of Prentiss and State of Mississippi, have invented a new and valuable Improvement in Feed-Cutters; and I do hereby declare that the following is a full, clear, and exact description of the construction and operation of the same, reference being had to the annexed drawings, making a part of this specification, and to the letters and figures of reference marked thereon.

Figure 1 of the drawings is a representation of an end view of my improved feed-cutter, showing the sash and knife; and Fig. 2 is a longitudinal vertical section thereof, showing the guard and the knife engaged between the plates *b* and *H*.

This invention has relation to improvements in feed-cutters wherein are employed a reciprocating sash carrying a cutter-blade, and operated by a lever to divide the feed into lengths; and the nature of the invention consists in the arrangement and novel construction of the various devices used, whereby very important results are obtained, all as will be hereinafter more fully set forth and claimed.

In the annexed drawings, the letter *A* designates a preferably inclined hopper, supported upon legs *B*. *C* represents a sash, of suitable construction, which is vertically movable in ways *a* on the inner faces of two uprights, *D* *D'*, at the ejection end of the hopper, and is provided with a cutting-blade, *E*, inclined to produce a draw-cut when it is thrust down past a preferably steel plate, *b*, upon the edge of the said hopper. *F* represents a vertically-vibrating lever, fulcrumed at *c* in a slot, *d*, in upright *D*, and extending through a slot, *d'*, in the other upright *D'*. This lever is connected by means of a pitman, *G*, with sash *C*, above described, and when it is operated will impart a vertically-reciprocating movement to the said sash, thereby thrusting the blade past plate *b*, and raising it up therefrom. During such operation lever *F*, being fulcrumed in slot *d* and working in slot *d'*, will be accurately guided during its vibrations, and held against lateral displacement, and, being connected by a pitman with the sash, the reciprocations of the latter will be strictly vertical, and attended with the least possible

friction, thus obtaining from the lever its full power. *H* represents a second metallic plate, upon the same level as plate *b*, and separated therefrom by an interval equal to the thickness of the cutter-blade. The feed to be cut will lie across this interval, and will be accurately divided when the blade is thrust down into the same, the effect of the outer plate being to prevent the jamming of straw, hay, or fodder between the cutter and plate *b*, which frequently occurs in damp weather, or when the feed is not thoroughly dry, in other machines. Plate *H* is secured upon the upper edge of a board, *K*, arranged between the legs *B* of the hopper, the ends of the said plate being bent down into spaces *g* cut in the vertical edges of the said board to allow the side rails *h* of the sash free movement up and down, thus serving the double purpose of positively holding the plate against all displacement, and guiding the sash in its downward movements. *I* represents a gage, secured across sash *C*, and designed to secure the division of the feed into equal lengths. When the blade comes in contact with the feed, this gage will be above the level of the bottom of the hopper and the blades *b* *H*, and the length of the cut will be regulated thereby. *J* represents an inclined guard, arranged in grooves in the sides of the hopper, beneath which the feed is passed to the knife. This guard is designed to prevent the hand of the operator from getting under the knife, and is vertically adjustable, for the purpose of providing for the passage under the same of bundles of feed of various thicknesses, the desired adjustment being maintained by means of a set-screw, *S*, passing through the side of the hopper against the end of the guard.

In order to provide for the removal of the sash to sharpen the knife *E*, the cross-piece *L* connecting the upper ends of uprights *D* *D'* will be hinged to the former, the necessary bracing of the said uprights being secured by means of a hook, *l*, and an eye, *m*, respectively, on the upright *D'* and the free end of cross-piece *L*. If this cross-piece be thrown up, and pin *c* removed, the sash and lever *F* may be drawn bodily out of their respective places, and the removal or sharpening of the knife readily accomplished.

What I claim as new, and desire to secure by Letters Patent, is—

1. In combination with a vertically-reciprocating knife, E, and hopper A, the vertically-adjustable guard J and set-screw S, substantially as specified.

2. In combination with the slotted uprights D D', carrying sash C, the cross-piece L, adapted to be thrown up out of the way, as and for the purpose set forth.

In testimony that I claim the above I have hereunto subscribed my name in the presence of two witnesses.

RUFUS NORTEN BOREN.
